UNITED STATES PATENT OFFICE.

HORACE C. GARDNER, OF CHICAGO, AND FRITZ A. LINDBERG, OF EVANSTON, ILLINOIS.

REFRIGERATING APPARATUS.

1,373,231.

Specification of Letters Patent. Patented Mar. 29, 1921.

Application filed August 4, 1919. Serial No. 315,139.

To all whom it may concern:

Be it known that we, HORACE C. GARDNER and FRITZ A. LINDBERG, citizens of the United States, residing, respectively, at Chicago, in the county of Cook and State of Illinois, and Evanston, in the county of Cook and State of Illinois, have invented a certain new and useful Improvement in Refrigerating Apparatus, of which the following is a full, clear, concise, and exact description, reference being had to the accompanying drawings, forming a part of this specification.

Our invention relates to refrigerating apparatus and broadly stated, our invention contemplates an apparatus of this class that can be easily and economically installed, that is extremely efficient and one which, for its successful operation, requires no special devices aside from the brine spray nozzles for establishing and maintaining a draft of cold air past and around the dressed meat or other products undergoing refrigeration.

While the nature of our invention requires that its structural embodiments shall vary within rather wide limits in order to meet various refrigeration problems and in order to successfully install our refrigerating equipment in structures not originally designed to have the equipment installed therein, the refrigerating equipment more or less diagrammatically illustrated in the accompanying drawings, may be considered typical of the several forms taken by our invention in actual practice.

Since a description of our invention will be best understood when read in connection with drawings illustrating the same, we shall proceed at once to a description of the accompanying drawings, in which,

Figure 1 is a view partly in section and partly in elevation illustrating a refrigerating apparatus embodying our invention, and

Fig. 2 is a horizontal sectional view taken on the line 2—2 of Fig. 1.

Similar characters of reference refer to similar parts in both figures.

The refrigerator shown more or less diagrammatically comprises side walls 10—10 and 10^a—10^a, the top or roof 11 and bottom or floor 12, all preferably lined with heat insulation such as cork, or a composition of cork and asphalt indicated at 13, the said lining, where necessary, being protected with galvanized iron sheeting or other pro-

tection covering illustrated at 13^a. The refrigerator is also provided with as many doors 15—15 as may be necessary or desirable. The ceiling indicated at 16 is preferably of material capable of resisting the corrosive action of the brine, which as will presently be described, is the agent we prefer to employ for cooling and circulating the air in the refrigerator. The brine proofing material preferably covers the refrigerator side walls for a substantial distance below the ceiling as shown at 17—17, the same being conformed at one point to provide a curved deflector 18 which extends entirely across one side of the refrigerator. Our invention is not particularly concerned with any of these parts of the refrigerator, the details of which may, of course, be varied within very wide limits.

At 19 is illustrated a brine pan of brine proofing material which divides the refrigerator into two principal compartments, to wit, the spray loft 19^a and chilling chamber 20. The chilling chamber is provided with any suitable means for supporting the dressed meat or other products under refrigeration, as, for instance, the track 21 carried by track supporting timbers 22.

It will be noted that the brine pan extends entirely across the refrigerator between the walls 10—10^a of the latter, but terminates short of the walls 10—10 to afford communication between the chilling chamber and the ends of the spray loft. The brine pan is supported in any suitable manner as, for instance, by a frame-work comprising the joists 23—23, the under side of the brine pan preferably being provided with a suitable heat insulating lining 24 of cork or cork and asphalt to prevent condensation of moisture on the under side of the brine pan and the under side of the floor 25, upon which the brine pan and heat insulation 24 are disposed. The escape of brine from the brine pan, by any avenue except the drain pipe, hereafter mentioned, is prevented by the refrigerator side walls 10—10^a and by suitable heat insulated ledges 25' and 26, which prevent the escape of brine over those edges of the brine pan which terminate short of the refrigerator walls 10—10.

It will be noted that the brine pan as viewed in Fig. 1 slopes from right to left and is provided with a drain 27 communicating with piping 28 leading to a brine mixing and storage tank 29, located at any suit-

able point, for convenience here illustrated as positioned under the refrigerator floor 12. A suitably supported trough 30 is preferably disposed under the lower edge of the 5 curved deflector 18, this trough being provided with means in the form of a drain 31 for carrying the moisture which drips off the deflector 18 to the brine pan. If desired, a deflector 32 may extend downwardly from 10 the lower edge of the brine pan to cause the current of chilled air, created as will presently be described, to pass downwardly a substantial distance before it circulates across the chilling chamber. We contemplate 15 the use of deflectors of this kind wherever they will improve the operation of the system as a whole.

A pump 33, the intake-port of which communicates with the mixing and storage tank 20, discharges brine under pressure through pipe 34, past check-valve 35 to a cooler of any suitable construction, which has been illustrated at 36. From the cooler the brine is led through pipe-line 37 to the nozzle carrying pipes 38, 39 and 40, which are disposed parallel to each other above the brine pan and have their closed ends supported in any suitable manner as, for instance, by brackets 41-41.

30 Each of the pipes 38, 39 and 40 is provided with a plurality of spray nozzles 42-42, all of which discharge in the same direction across the spray loft toward the low edge of the brine pan. The several nozzles 35 may be of any well known construction but we prefer to employ nozzles of the type capable of discharging a liquid under pressure in the form of a whirling spray. Such nozzles are well known and the details 40 thereof need not be described here. As is clearly shown in Fig. 2, the several nozzles are so disposed that, when they are all discharging spray in the same direction, the said spray substantially fills the loft in the vicinity of the pipes 38, 39 and 40 and for a substantial distance to the left of pipe 40 (Fig. 1) with the result that a rapid circulation of air is set up in the direction indicated by the arrows in Fig. 1. The violence 45 of this circulation is, of course, dependent upon the dimensions of the brine loft, the size and number of the nozzles and the pressure under which the cold brine is supplied to the nozzles. Since the cold 50 brine spray comes into intimate contact with the air which is caused to circulate through the loft it will be understood the air is rendered very cold before it leaves the loft and circulates through the chilling 55 compartment 20.

60 While we do not limit ourselves to any specific arrangement of the spray nozzles, we have found that the system is very effective when the nozzles discharge in parallel 65 rows and in tandem as herein illustrated.

A very effective arrangement is to provide the pipe 38 with a large number of equally spaced spray nozzles and to provide each of the pipes 39 and 40 with half as many nozzles, with the nozzles carried by the pipes 70 39 and 40 in staggered relation to each other. While this arrangement is very effective, it is but one of a number of arrangements that may be used to accomplish the same result.

We do not limit ourselves to the specific 75 construction and arrangement of parts herein shown and described, but desire to claim all equivalent embodiments of our invention as defined by the appended claims.

Having thus described our invention, 80 what we claim as new and desire to secure by Letters Patent of the United States is:—

1. In a refrigerating apparatus a chilling compartment, a spray loft thereabove, said chilling compartment communicating with 85 said spray loft on the opposite sides of the latter and means for causing air to circulate through said spray loft and said chilling compartment comprising a plurality of nozzles in said spray loft all adapted to discharge a cold fluid under pressure into said spray loft in the same direction. 90

2. A refrigerating apparatus comprising a chilling compartment and a spray loft, said chilling compartment opening into the 95 spray loft on two sides of the latter, together with means in said spray loft for circulating and cooling air, said means comprising a plurality of spray nozzles discharging into said spray loft in parallel 100 rows and in tandem to impel the circulation of air through said spray loft and said chilling compartment, together with means for supplying said spray nozzles with cold fluid under pressure. 105

3. A refrigerating apparatus comprising a chilling chamber and a spray loft, the chilling chamber communicating with the spray loft on opposite sides of the latter and a plurality of spray nozzles arranged 110 in parallel rows and in tandem, all of said spray nozzles discharging into the spray loft in one direction substantially to fill the spray loft with spray in the vicinity of the nozzles to impel the circulation of air through the loft and said chilling chamber and means for supplying said nozzles with cold liquid under pressure. 115

4. A refrigerating apparatus comprising a chilling chamber, a spray chamber adjacent thereto, said spray chamber communicating at its ends with the chilling chamber and means arranged to discharge cold liquid spray under pressure end-wise into said spray chamber to impel a circulation of air 120 through said spray chamber and chilling chamber and to cool the air as it passes through said spray chamber. 125

5. A refrigerating apparatus comprising a chilling chamber, a spray chamber adj- 130

cent thereto, said spray chamber communicating at its ends with the chilling chamber, a plurality of spray nozzles in said spray chamber, said nozzles arranged in a 5 plurality of parallel rows and means for supplying said nozzles with cold liquid under pressure, all of said nozzles adapted to discharge a finely divided spray directed end-wise into said spray chamber substantially to fill the spray chamber with cold

spray in the vicinity of the nozzles to impel the circulation of air through the spray chamber and to chill the air as it passes through said spray chamber.

In witness whereof, we hereunto subscribe our names this 29th day of July, 1919.

HORACE C. GARDNER.

FRITZ A. LINDBERG.

Witness:

A. G. McCaleb.
